US0D1113015S

(12) **United States Design Patent** (10) Patent No.: **US D1,113,015 S**
(45) Date of Patent: ** Feb. 10, 2026

(54) **VACUUM CLEANER**

(71) Applicant: **Wuhan Chuangxian Technology Co., Ltd.**, Wuhan (CN)

(72) Inventors: **Yi Cai**, Wuhan (CN); **Tianyu Pan**, Wuhan (CN); **Zuling Song**, Wuhan (CN); **Run Wang**, Wuhan (CN); **Chong Xia**, Wuhan (CN); **Yazhou Fan**, Wuhan (CN)

(73) Assignee: **Wuhan Chuangxian Technology Co., Ltd.**, Wuhan (CN)

(**) Term: **15 Years**

(21) Appl. No.: **29/923,421**

(22) Filed: **Dec. 29, 2023**

(51) LOC (15) Cl. **15-05**

(52) U.S. Cl. **D32/21**
USPC **D32/21**

(58) **Field of Classification Search**

USPC D15/19; D21/526, 578; D32/15, 16, 19, D32/20, 21, 38
CPC A47L 5/00; A47L 5/12; A47L 5/22; A47L 11/00; A47L 11/24; A47L 11/32; A47L 11/33; A47L 2201/00; A47L 2201/04; A47L 2201/06; B08B 1/00; B08B 1/30; B08B 1/32; B08B 1/34; B08B 1/36

(57) **CLAIM**

The ornamental design for a vacuum cleaner, as shown and described.

DESCRIPTION

FIG. 1 is a front perspective view of a vacuum cleaner, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

1 Claim, 8 Drawing Sheets
